United States Patent Office

Des. 221,766
Patented Sept. 7, 1971

221,766

AIRCRAFT RADIO ANTENNA

William C. Rogers, 5365 NW. 36th St.,
Miami Springs, Fla. 33166

Filed Jan. 15, 1970, Ser. No. 20,944

Term of patent 14 years

The portion of the term of the patent subsequent to
May 27, 1983, has been dedicated to the Public

Int. Cl. D14—03

U.S. Cl. D26—14

FIG. 1 is a side elevation of an aircraft antenna showing my new design, the opposite side is a mirror image of the side shown;

FIG. 2 is a top plan view thereof;

FIG. 3 is a bottom plan view thereof;

FIG. 4 is a front elevation thereof;

FIG. 5 is a rear image thereof;

FIG. 6 is a side elevation of a modified embodiment of the aircraft radio antenna illustrated in FIG. 1, the opposite side is a mirror image of the side shown;

FIG. 7 is a top plan view thereof;

FIG. 8 is a bottom plan view thereof;

FIG. 9 is a front elevation thereof;

FIG. 10 is a rear elevation thereof;

FIG. 11 is a side elevation of a third embodiment of the aircraft radio antenna illustrated in FIG. 1;

FIG. 12 is a top plan view thereof;

FIG. 13 is a bottom plan view thereof;
FIG. 14 is a front elevation thereof; and
FIG. 15 is a rear elevation thereof.

I claim:

The ornamental design for an aircraft radio antenna, substantially as shown and described.
